WELDER'S HELMET

Filed June 12, 1945

UNITED STATES PATENT OFFICE

2,433,164

WELDER'S HELMET

Raleigh T. Shields, Newport News, Va.

Application June 12, 1945, Serial No. 598,963

4 Claims. (Cl. 2-8)

1

This invention relates to a novel and improved welder's helmet and more particularly to an eye protecting shield, its construction and method and means of mounting same on the helmet frame to satisfactorily achieve the desired ends.

Briefly, the preferred embodiment of the invention is characterized by an endless circular band to embrace the head and temples of the wearer, this being attached on opposite sides to the helmet, there being a pair of suitably shaped arms hingedly connected at their rear ends to corresponding portions of said band, and these latter arms being attached to an appropriate eye protecting shield which can be conveniently swung down when in use, or swung up to an out-of-the-way position beneath the helmet.

The principal object of the invention, obviously, is to provide a suitable welder's helmet with an adequate type of eye shield which may be moved out of the way or brought into position whenever necessary or desired depending on the circumstances, said shield serving to protect the eyes against the flying hot flux and metal, and also from the arcs of other welders nearby.

Other objects, features and advantages will become more readily apparent from the following description and the accompanying illustrative drawings.

In the drawings, wherein like numerals are employed to designate like parts throughout the same:

Figure 1 is a side view showing the eye shield equipped welder's helmet as constructed in accordance with the principles of the instant invention and portraying the manner in which it is worn and used, a portion of one side being broken away to expose the structural details therebeneath.

Figure 2 is a fragmentary view showing a portion of the helmet on one side and bringing out the top plan and configuration of the head band and eye shield attachment, other parts being purposely omitted for clearness of emphasis of the main parts.

Figure 3 is a section which may be said to be taken approximately on the plane of the line 3-3 of Figure 2.

Figure 4 is a view somewhat similar to Figure 2, this bringing out, partly in perspective, the shape and formation of the details.

Figure 5 is a view which may be said to be taken approximately on the plane of the line 5-5 of Figure 1 bringing out the parts on a larger scale.

Referring to the drawings by distinguishing reference numerals, the helmet, which is of ap-

2

propriate shape and materials is denoted by the numeral 7. This preferably conforms to the shape and size of a regular welder's helmet and is positioned to extend out so as to provide clearance space between itself and the forehead to accommodate the eye shield, permitting same to be raised and pushed up under and between the helmet and head when not in use, or brought down to the useful position illustrated in Figure 1. In order to achieve the desired ends, I employ a substantially circular slightly downwardly and outwardly slanted band or adapter 8. This surrounds the head as shown and also embraces the temples of the wearer, the opposite median portions thereof being pinned, as at 9, to adjacent edge portions of the shell of the helmet. Either a bolt or a screw may be employed, this as brought out in Figure 5, the same being surrounded at inner and outer end portions by short spacing sleeves 10 and 11. The numerals 12 designate outstanding stop or rest pins carried by the band 8 which are of appropriate dimensions and shape and these accommodate the horizontal reaches or portions of the duplicate eye-shield arms 13. The rear or inner ends of the arms 13 are formed into suitable eyes 14 hingedly mounted on the pins 9 on opposite sides of the helmet. When the arms are down, that is in horizontal and useful positions as seen in Figure 1 they rest on the outstanding stop pins which pins serve to keep them in the thus elevated position. The outer ends of the arms are directed laterally and downwardly as indicated at 15 and they are then attached as at 16 to a substantially arcuate channel-shaped frame member 17 which carries the detachable eye shield 18. This is of appropriate fireproof transparent material and, in practice, may be suitably colored, for instance colored green for restfulness to the eyes of the wearer.

When it is not necessary or desired to utilize the eye shield 18 in a position in front of the wearer's eyes it can be swung up to an out-of-the-way position. That is to say, the user can simply grasp the eye shield and lift it up by hand and then move it to a position over the top or crown of his head in which position it takes a horizontal setting. Also, if the visor or helmet 7 is at the same time in a correspondingly horizontal position, the eye shield 18 takes a position between the helmet and the head of the wearer. When the eye-shield 18 is in this up and out-of-the-way position, I have found it necessary to provide a suitable latch means to hold it there. Said means may involve the use of either one or two latches. For the moment it is to be as-

sumed that there is a single latch under consideration. Each latch is of the construction shown in Figure 5; that is to say, it comprises a slidably mounted pin having a knurled finger grip which is accessible through and beyond one side of the helmet, the shank of the pin being slidable in an aperture in said helmet. The pin is held in normally projected or locking position by a coiled spring 21 bearing against a suitably arranged stop shoulder 22. When the arms 13 and companion eye-shield 18 are both "down" and the face shield 7 is simultaneously down (see dotted lines in Figure 1), the latch pin 19 is then snapped into the aligned keeper slot 23. With both shields 7 and 18 latched together they may be swung conveniently up and over the wearer's head to assume out-of-the-way positions. Also, said shields may be operated and used independently; that is, the shield 7 may be shoved up and self retained over the wearer's head, while the other shield 18 may be dropped down for use, as shown in full lines in Figure 1. By the same token, and assuming that the shield 7 is up and the user wants to lift the eye-shield 18 and locate same between the shield 7 and the top of his head, this too can be accomplished and said shields again latched together for proper maintenance.

The gist of the invention is in the provision of a comfortably and appropriately shaped helmet, this to accommodate, by suitable clearance, the circular head and adapter band, the latter assisting in supporting the helmet in place, also serving as an effective complementary part for the opposed pairs of arms which serve in turn, to suspend and hingedly mount the arcuate eye shield.

With further reference to the aforementioned spring pressed latches or detents 19, it will be observed that when the helmet 7 swings up and over the head and assumes a horizontal position as illustrated in Figure 1, it will carry the eye shield 18 up with it. In other words, the eye shield will maintain the same spaced parallel relation to the helmet and both parts will swing up as a unit. However, if it is desired, the helmet can be released by disengaging the latch and swung up independently leaving the eye shield in the down position shown in full lines in Figure 1. Then when the helmet is returned to its normal face shielding position as shown in dotted lines in Figure 1, the latch 19 will have to be re-engaged with the keeper slot 23. These are, however, obvious phases of the invention such as will be clear to persons skilled in the art to which it relates.

In practice I contemplate using either one or two of said latches, depending on requirements of the trade.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a structural assemblage of the class described, in combination, a welder's helmet, a circular band adapted to embrace the head and tem-

ples of the wearer, said helmet being hingedly mounted on said band arms also hingedly mounted on the band, and an eye shield connected to the outer ends of said arms, the band being provided with stop pins and said arms resting on said stop pins when in a "down" position, one of said arms having a keeper slot, and a releasable spring retained latch mounted on the helmet and engageable with the keeper slot to hold the arms and eye shield in an up and out-of-the-way position when the helmet is in a raised position.

2. A combination welder's helmet and companion eye-shield comprising a head encircling band, a welder's helmet comprising a face shield having a sight opening and wing portions hingedly mounted on substantially diametrically opposite portions of the head encircling band, arms hingedly mounted on said head encircling band between the band and surrounding face shield, an eye-shield connected to said arms, at least one of said arms having a keeper means, releasable latch means mounted on the face shield and engageable with said keeper means in order to permit the eye-shield and face shield to work either in unison, or independently of one another, as the case may be.

3. A combination welder's helmet and companion eye-shield comprising a head encircling band, a window equipped welder's helmet comprising a face shield having wing portions hingedly attached to substantially diametrically opposite portions of the head encircling band, arms hingedly connected at their rear ends to said head encircling band at points between the band and surrounding face shield, an eye-shield connected to said arms, one of said arms having a keeper slot, a spring pressed retaining latch mounted on the face shield and releasably engageable with said keeper slot in order to permit the eye-shield and face shield to be raised and lowered either in unison, or independently, as the case may be, together with stop elements carried by said head encircling band, said arms being adapted when in lowered position to rest against said stop elements.

4. In a combination welder's helmet and companion eye-shield arrangement, head embracing means, a welder's helmet comprising a face shield having portions hingedly attached to substantially diametrically opposite portions of said embracing means, a pair of complementary arms hingedly connected at their rear ends to diametrically opposite side portions of said embracing means, an eye-shield connected to the outer swingable ends of said arms, outstanding stop elements mounted on said embracing means with which said arms are engageable, and manually controllable latch means carried by said face shield and releasably connectible with a coacting portion of at least one of said arms in the manner and for the purposes described.

RALEIGH T. SHIELDS.
